UNITED STATES PATENT OFFICE.

ROBERT H. BUSCH, OF COLUMBUS, GEORGIA.

COLLAR SUPPORTER.

Application filed March 10, 1925. Serial No. 14,445.

This invention relates to improvements in collar supporters, and is more particularly adapted to a device for supporting a collar on the neck band of a uniform coat such as is worn by officers.

One of the important objects of the present invention is to provide a collar supporter of the above mentioned character which will enable a linen collar to be attached to the inner face of a neck band of a uniform coat in such a manner as to enable the collar to be readily positioned to project to the desired extent above the neck band.

A further object is to provide a collar supporter of the above mentioned character which may be readily and easily attached to the inner face of the neck band for securing a collar thereon, the device being of such construction as not to cause any discomfort to the wearer.

A further object is to provide a collar supporter of the above mentioned character which is simple in construction, inexpensive, and furthermore adapted to the purposes for which the same is designated.

Other objects and advantages of this invention will become apparent during the course of the following description.

In the accompanying drawing forming part of this specification and in which like numerals are employed to designate like parts throughout the same:—

Figure 1 is a front elevation of the device showing the same attached to the neck band and the manner in which a collar is secured.

Fig. 2 is a sectional view taken approximately on line 2—2 of Fig. 1, and

Fig. 3 is a detail perspective view of the collar supporter embodying my invention.

In the drawing, wherein for the purpose of illustration is shown the preferred embodiment of my invention, the numeral 1 designates generally my improved collar supporter, the same being shown with a single piece of spring metal and comprises the base plate 2 which is of substantially rectangular design.

A pair of laterally extending apertured ears 3 are formed on the lower end of the base plate, a similar pair of ears 4 extending upwardly in diverging relation with respect to each other from the upper end of the base plate. These ears are adapted to be attached to the canvas stiffening 5 of the neck band 6 such as is provided on a

uniform coat which is worn by Army officers, and the like.

The lining which is stitched to the inner face of the neck band and covers the inner face of the transverse stiffening is indicated at 7. The base plate 2 will therefore be interposed between the canvas stiffening and the lining 7 as is clearly illustrated in Figs. 1 and 2 of the drawing.

Formed on the lower end of the base plate 2 is the relatively narrow elongated tongue 8, the same tapering gradually toward its outer free end and terminating in the laterally extending or pointed prong 9, the purpose of which will be hereinafter more fully described. The tongue 8 is bent back upon the base plate. The tongue 8 is adapted to extend through the lining 7 and be disposed on the outer face thereof as clearly illustrated in Figs. 1 and 2.

Three of such collar supporters are preferably attached to the inner face of the neck band of a uniform coat, two of these supporters being arranged adjacent the free ends of the neck band while the other is located at the back or central portion of the neck band. The linen collar which is usually worn with neck bands of the above mentioned character is illustrated at 10 and

the same is placed adjacent the outer face of the neck band of the lining 7 and adjacent the inner side of each of the tongues 8. The collar may be readily positioned to project to the desired extent above the neck band and when properly positioned, the prong 9 of each of the tongues is forced

into engagement with the collar 10 in a manner as clearly illustrated in Fig. 2, whereby the collar will be secured against accidental displacement from the neck band, yet permitting the collar to be readily and easily detached whenever it becomes necessary.

The provision of a collar supporter of the above mentioned character will not cause any discomfort to the wearer and may furthermore be readily and easily operated. The simplicity in which my improved collar supporter is constructed, renders the same inexpensive in its manufacture.

While I have shown the preferred embodiment of my invention, it is to be understood that various changes in the size, shape and arrangement of parts may be resorted to without departing from the spirit or scope of the appended claim.

2
Having thus described my invention, what I claim as new is:—

- As a new article of manufacture, a collar supporter for uniform coats adapted to be stamped from a single blank of spring metal and comprising a base plate of substantially rectangular design, apertured ears formed at the corners of the rectangular base plate and providing a means for attaching the same to the inner face of the neck band of the coat, a tongue formed on the lower end of the plate and tapering

gradually toward its free end, said tongue being of greater length than the base plate and being bent back upon the plate, the upper free end of the tongue terminating in a laterally projecting prong which is disposed inwardly above the upper end of the plate, said prong adapted to engage and support a collar on the inner face of the neck band. 15 20

In testimony whereof I affix my signature.

ROBERT H. BUSCH.
